UNITED STATES PATENT OFFICE

146,418

DESIGN FOR A PORTABLE PASSENGER LOADING STAND OR SIMILAR ARTICLE

John Louis Olivarez, Los Angeles, Calif., assignor
to Airquipment Company, Burbank, Calif.

Application March 7, 1946, Serial No. 127,177

Term of patent 14 years

(Cl. D14—3)

To all whom it may concern:

Be it known that I, John Louis Olivarez, a citizen of the United States, residing at Los Angeles, in the county of Los Angeles and State of California, have invented a new, original, and ornamental Design for a Passenger Loading Stand or Similar Article, of which the following is a specification, reference being had to the accompanying drawings, forming a part thereof.

Figure 1 is a front perspective view of a portable passenger loading stand embodying the new design as it appears from a point forward of and slightly to one side of the stand;

Figure 2 is a perspective view of the stand as it appears from a point rearwardly of and slightly to one side of the stand;

Figure 3 is a side elevational view thereof, and, Figure 4 is a front elevational view thereof.

I claim:

The ornamental design for a portable passenger loading stand or similar article, substantially as shown.

JOHN LOUIS OLIVAREZ.
